UNITED STATES PATENT OFFICE

CHRIST S. MINNECI, OF CHICAGO, ILLINOIS

TRANSOM CONTROLLER

Refiled for abandoned application Serial No. 215,218, filed February 2, 1918. This application filed May 2, 1929. Serial No. 359,971.

This invention relates to new and useful improvements in transom controllers, being a refiling of application filed Feb. 2, 1918, Serial No. 215,218, abandoned March 7, 1924, 5 and the principal object of the invention is to provide a device adapted for opening and closing ordinary hinged transoms by the mere pulling of a chain.

Another object of the invention is to provide a spring for holding the transom in either open or closed position which spring holds the device in either of its positions and also acts to move the same when the connecting links are in proper position for such 15 movement.

A still further object of the invention is to provide a transom opener consisting of an elbow joint which is provided with a means for breaking the joint in order to enable 20 the spring to act.

With these and other objects in view the invention consists in the novel combination and arrangement of parts which will be fully set forth in the following specification and 25 accompanying drawings, in which:—

Figure 1 is a face view of a transom showing this opener applied thereto,

Figure 2 is a sectional view on line 2—2 of Figure 1 showing the same on an enlarged 30 scale and illustrating the transom closed,

Figure 3 is a view illustrating the transom opened, and

Figure 4 is a diagrammatic view of the device showing the method of operation.

Referring to the drawings the numeral 1 35 designates an ordinary door casing having hingedly connected thereto the transom 2 which is preferably hinged at its lower edge to the lintel and is arranged to open in the ordinary way. Attached to the transom near 40 its upper edge is the inwardly extending arm 3 provided with an angular extension at its inner end which is connected to one end of the elbow which will be more fully herein- 45 after described. The arm 3 forms the controlling arm by means of which the transom is moved.

Secured to the casing 1 is a plate 5. This 50 plate 5 is formed with an outwardly extending ear 6 to which a link 7 is pivoted and this

link extends outwardly therefrom and is provided near its outer end with a stop 8 while a suitable aperture 9 is provided near the inner end of said link and is adapted to receive the hooked end of a suitable connecting element for the spring which will be more fully hereinafter described. The extreme outer end of the link 7 is pivotally connected as at 10 to a link 11 the opposite end of which is apertured to pivotally receive the end of 60 the arm 3. An extension 12 is formed on the link 11 and projects beyond the end to which the link 7 is pivoted and this extension 12 is apertured as at 13 to receive the uppermost link of a suitable chain 14 or other suitable 65 flexible member. This extension 12 is adapted to engage the stop 8 when the transom is in open position and thus the links 7 and 11 are prevented from moving beyond a predetermined point. 70

Extending through the opening 9 is a suitable hook 15 formed at the lower end of a connecting element 16, the upper end of which is provided with an eye 17 to which the lower end of a tractile coil spring 18 is 75 connected. The upper end of said coil spring is connected to a screw eye 19 which is attached to the casing 1.

It will be apparent from the foregoing that in use assuming that the transom is closed, pull is exerted on the chain 14 thus causing the link 11 to swing on the pivot 10 and tend to pull the upper end of said link outwardly thus moving the transom on its hinge. The swinging movement of the transom will swing the link 11 beyond the perpendicular and simultaneously swing the link 7 downwardly until the links assume the positions shown in Fig. 3 at which time the transom is fully open. When it is desired to close the transom, pull is again exerted on the chain 14 thus breaking the elbow joint formed by the links 7 and 11 and due to the pull of the spring 18 the transom will be moved to closed position. 80

While in the foregoing there has been shown and described the preferred embodiment of this invention, it is to be understood that such changes may be made in the combination and arrangement of parts as will 85 90 95 100

fall within the spirit and scope of the invention as claimed.

What is claimed is:—

In a closure operator, the combination with a hinged closure and a fixed support, a link pivoted to said closure, a second link, said second link being pivoted to said fixed support and at a point intermediate its ends to the first link to provide a free end extension on the first link beyond the last mentioned pivot, a spring connected to the second link adjacent its pivotal connection with the fixed support and connected to the fixed support substantially above the last mentioned pivotal connection, a flexible operating member connected to the extension, and a stop on said second link to cooperate with said extension when the closure is in fully opened position, said spring operating to hold the hinged closure in closed position in one adjustment of said links and in another adjustment with the extension engaging the stop holding the links in extended relation with the closure in open position, pull on said flexible member in the same direction and against the tension of said spring operating to release the closure from its position either when open or closed, the tension of the spring completing the movement when pull on the flexible member is relieved.

In testimony whereof I affix my signature.

CHRIST S. MINNECI.
